US0D1096778S

(12) **United States Design Patent** (10) **Patent No.:** **US D1,096,778 S**
(45) **Date of Patent:** **** Oct. 7, 2025**

(54) **DISPLAY SCREEN HAVING A GRAPHICAL USER INTERFACE**

(71) Applicant: **Evernorth Strategic Development, Inc.**, St. Louis, MO (US)

(72) Inventors: **Allyson Busch**, Orlando, FL (US); **Taylor Gordon-Wood**, Orange City, FL (US); **Keith R. Melillo**, Lake Mary, FL (US); **Ria Westergaard**, Caledonia, IL (US)

(73) Assignee: **Evernorth Strategic Development, Inc.**, St. Louis, MO (US)

(**) Term: **15 Years**

(21) Appl. No.: **29/886,649**

(22) Filed: **Mar. 10, 2023**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen having a graphical user interface, as shown and described.

DESCRIPTION

The FIGURE is an image of a display screen having a graphical user interface, showing the new design.

The broken lines in the figure show a display screen or portion thereof, and form no part of the claimed design.

1 Claim, 1 Drawing Sheet
